UNITED STATES PATENT OFFICE.

ERVIN L. YUNCKER, OF DODGE CITY, KANSAS.

WASHBOARD.

1,314,297.

Specification of Letters Patent. Patented Aug. 26, 1919.

Application filed January 4, 1919. Serial No. 269,614.

To all whom it may concern:

Be it known that I, ERVIN L. YUNCKER, a citizen of the United States, residing at Dodge City, in the county of Ford and State 5 of Kansas, have invented certain new and useful Improvements in Washboards, of which the following is a specification.

This invention relates to wash boards and more particularly to the rubbing surfaces 10 thereof.

The object of the invention is to provide a wash board having a yieldable working face or mat formed with projections whereby to present a roughened surface to the 15 clothes and permit the latter to be thoroughly cleaned without danger of tearing or mutilating the fabric during the washing operation and without injury to the hands of the user.

20 The invention further aims to provide novel means for securing the mat in position on the back plate and both in the side bars, and also to so construct said back plate that the upper and lower portions thereof 25 serve to house and protect the ends of the mat.

A still further object of the invention is generally to improve this class of devices so as to increase their utility, durability and 30 efficiency.

Figure 1 is a perspective view of a wash board provided with a yieldable rubbing surface embodying the present invention;

Fig. 2 is a detailed vertical sectional view 35 taken on the line 2—2 of Fig. 1;

Fig. 3 is a detailed transverse sectional view taken on the line 3—3 of Fig. 1;

Fig. 4 is a perspective view of the back plate of the wash board detached;

40 Fig. 5 is a perspective view illustrating a modified form of the mat.

Corresponding and like parts are referred to in the following description and indicated in all the views of the drawings by 45 the same reference characters.

The improved wash board forming the subject-matter of the present invention comprises spaced side bars 5 connected at their upper ends by a top piece 6 and having their 50 lower ends shaped to form supporting legs 7. Seated in channels 7' formed in the side bars 5 and rigidly secured in any suitable manner as by nails or similar fastening devices 8, is a back plate 9. The back plate

9 is preferably of integral formation and 55 the central portion thereof is bulged or thickened to provide a flat face 10 over which extends a yieldable rubbing surface, indicated as a whole at 11. Formed in the opposite ends of the back plate 9 are inclined seating grooves 12 adapted to receive 60 the adjacent ends of the rubbing surface 11, said grooves defining overhanging retaining lips 13 which bear against and serve to house and protect the adjacent ends of 65 said rubbing surface. The bottoms of the grooves are spaced from the adjacent ends of the back plate while the rear walls at the open ends of the grooves gradually merge into the flat face 10, as indicated at 70 14, so as not to present any sharp projections which would tend to cut or otherwise mutilate the rubbing surface. The rubbing surface 11 is a mat preferably molded or otherwise formed of rubber and the rear 75 face thereof is provided with a canvas backing 15, while the front face is provided with a plurality of spaced substantially frusto pyramidal projections 16. By means of these or similar projections of rubber, 80 sufficient friction is produced between the said surface and the clothes to insure thorough washing thereof without danger of tearing or otherwise mutilating the fabric and without liability of lacerating or otherwise injuring the hands of the user. The frusto pyramidal projections are preferably omitted at the opposite ends of the rubbing surface or mat 11 so as to have plain margins 10' to enter the seating 85 grooves 12, and it will here be noted that when the margins are seated fully within the grooves 12 the adjacent frusto pyramidal projections will bear against the edges of the retaining lips 13 and assist in preventing 90 accidental displacement of said mat. If desired, suitable staples 17 may be driven through the mat and into the back plate 9 to assist in preventing accidental displacement of said mat. When 95 the staples are employed the closed ends thereof will bear directly against the rubber between adjacent projections so as not to tear or otherwise mutilate the clothes. The opposite side edges of the mat also 100 having plain margins which, together with the sides of the back board 9, fit within the channels 7' of the side bars 5, as best shown 105

in Fig. 3 of the drawings, so that the mat is securely held from both longitudinal and lateral displacement.

The opposite ends of the back plate 9 above and below the face 10 thereof are preferably reduced in thickness so that when the rubbing mat is positioned on the face 10 the intermediate portion will lie in a perpendicular plane while the opposite ends thereof will recede in the direction of the upper and lower ends of the wash board, as best shown in Fig. 2 of the drawings, and thus facilitate drainage and also present a substantially convex rubbing surface to the clothes.

In Fig. 5 of the drawings there is illustrated a modified form of the invention in which the yieldable rubbing surface is composed of transverse corrugations 8' and it will be understood that this form of rubbing surface or any other form may be employed in lieu of that shown in Fig. 1 if desired.

Having thus described the invention, what is claimed as new is:

A wash-board comprising side bars having channels in their inner faces, a back plate having transverse grooves in its front face near its upper and lower ends, each oblique to the plane of said face so as to provide an overhanging lip, the face being flat throughout most of its area and receding into and merging with the rear walls of said grooves, and a mat made up of a canvas backing and a superposed yieldable body having plain margins and a projecting roughened rubbing surface over the remainder of its area, its upper and lower margins seated in said grooves with the endmost projections against said lips, and its side margins together with the edges of the back plate seated in said channels with the extreme lateral projections against the inner faces of the side bars.

In testimony whereof I affix my signature. 45
ERVIN L. YUNCKER. [L.S.]
